DES. 1989

Robert G. Stanton, of West Farms, N.Y.

Letters Patent No. 1989 Sept. 30th 18

Design for a Skate.

The schedule referred to in the Letters Patent and making part of the same.

Be it known that I, Robert G. Stanton, of the Town of West Farms, County of Westchester and State of New York, have invented and produced a new pattern and design for the shape and configuration of a Skate, and do hereby declare that the following is a full or exact description of the same.

The foot or sole is made of wood painted or varnished as per annexed drawing A, with the heel and toe pieces or standards cast for in

the case of cast iron, forged iron, brass, or other suitable metal B. The standards are placed one under the heel with a screw C, passing through and projecting from the heel of the sole, the other under the ball and toe joints of the foot, they are composed of one upright piece of metal with branching arms D, and are firmly attached to the sole A, by suitable mechanical device.

The heel and toe pieces so formed connect the sole A to the runner E, and are grooved out at the lower ends of the uprights that they may straddle the runner, and be attached thereto by rivets at points F. The runner is

the ordinary slate runner, cast or forged in the usual manner from iron or steel, and comes in contact with the sole A at the point of the toe, all in conformity to the drawings herewith annexed, the whole forming what I claim as a design for a skate new and elegant in form and shape.
